UNITED STATES PATENT OFFICE.

WILLIAM H. THOMPSON, OF MEMPHIS, TENNESSEE, ASSIGNOR TO THOMPSON ELECTRIC CLOCK COMPANY, OF MEMPHIS, TENNESSEE, A CORPORATION OF TENNESSEE.

ELECTRIC AUTOMOBILE-CLOCK.

1,241,055.

Specification of Letters Patent. Patented Sept. 25, 1917.

Application filed October 28, 1914. Serial No. 869,014.

To all whom it may concern:

Be it known that I, WILLIAM H. THOMPSON, a citizen of the United States, residing at Memphis, county of Shelby, and State of 5 Tennessee, have invented certain new and useful Improvements in Electric Automobile-Clocks, of which the following is a specification.

This invention relates to electric automobile clocks.

The present invention embodies improvements on the electric automobile clock set forth in my Patent No. 1024709, dated April 30, 1912, but it has the same general object 15 in the provision of a clock intended for use on automobiles, locomotives, vessels, and other vehicles where more or less constant vibration exists and where winding of a spring clock would be neglected except at 20 irregular intervals, with resulting deterioration and inaccuracy in keeping time. Automobile clocks are peculiarly subject to neglect and this, with the excessive vibration, soon impairs their reliability as time keepers.

25 The clock set forth in my Patent No. 1024709 is well adapted to meet the requirements of automobile, railroad and marine service, but the object of the present improvements is to minimize any irregularity 30 of time keeping of a clock of that character; directly drive the center wheel of the movement by power applied to the periphery thereof and to deliver the power from the periphery of the center wheel to the train at 35 the same gear pitch; provide a bodily movable armature which may be made as a stamping and which is mounted so that the maximum magnetic attraction will be obtained and correspondingly improved winding 40 effect had; provide novel means and combinations whereby substantially the same winding effect is obtained, whether the battery current be weak or strong; combine the winding or actuating wheel and the power 45 maintaining means in an improved relationship; and, further, to generally improve the construction to the end that a more efficient and durable clock be provided.

In the clock set forth in my Patent No. 50 1024709, I employed a coil-spring disposed around the sleeve of the actuating or winding wheel and an armature which was pivoted intermediate its ends. With such a spring, an increasingly greater pressure is 55 required as the spring is wound tighter;

consequently, the tension of the spring, which is controlled by the armature, is dependent on the strength of the battery current, and this is particularly so because the armature lever is pivoted intermediate its 60 ends, and the winding action, being dependent on the leverage, is in turn, quite dependent on the current used to energize the electro-magnet. It will be seen, therefore, that with the construction of my Patent, No. 65 1024709, when the battery current becomes weak or drops below normal, the power spring is not tensioned as strongly as when the current is normal and, accordingly, with the old form of spring, when the battery is 70 fresh and the current maximum, the greater tension imparted to the power spring causes the clock to run faster than when the battery, from continued use, delivers a weaker current and does not tension the spring so 75 much.

In the present invention I provide an extensible coil spring, one end of which is anchored, as to the watch or clock frame, and the other end connected to an arm or 80 lever attached to or forming part of the driving or actuating wheel, preferably to the sleeve thereof. This arrangement affords an automatic compensation whereby as the tension of the spring is heightened, the leverage 85 exerted on the spring by the driving wheel is correspondingly or compensatingly decreased and the torque exerted on the driving wheel, and consequently the center wheel of the clock or watch train, is maintained 90 substantially the same, within the limits of play of the parts, whether the armature be attracted to the electro-magnet with a maximum, a minimum, or an intermediate effect. Consequently, whether the battery be weak 95 or strong, the operation of the clock or watch train is substantially constant.

In my Patent, No. 1024709, the armature lever is pivoted intermediate its ends. In the present invention, the armature lever 100 is pivoted at one end and is consequently arranged so that it is practically bodily movable. Its relationship to the poles of the electro-magnet is such that a portion of the armature is always within the magnetic field of one of said poles, and consequently, on the slightest magnetization of the electro-magnet, the armature is attracted and thereupon comes within the magnetic field of the other pole of the magnet, whereupon a 110

bodily movement and a maximum magnetic attraction of the armature results and it acts in a hammer-like manner to kick or snap the driving or winding wheel the desired distance. With this arrangement, a minimum battery current will cause adequate tensioning of the power spring and, due to the compensating construction hereinbefore referred to, the leverage exerted by 5 the spring will cause the driving torque on the center wheel to be substantially the same as what it would be if the battery current were greater and the action of the armature stronger, because with a stronger armature 10 action, as when the battery is fresh, the correspondingly greater extent of movement of the driving wheel and greater tension of the driving spring, is compensated for by the decreased leverage exerted by the driving spring when the arm has passed a certain point. I wish it understood that I do not limit myself to the use of an arm, in connection with the spring, as I may use 15 a cam, fusee or other part performing the same function.

The invention is carried out further, by the provision of an improved spring back-stop for the armature; and details of arrangement and combination of the driving 20 and power maintaining means, as also other details of construction, set forth more fully hereinafter.

In the accompanying drawings:

Figure 1 is a longitudinal section through 35 the case and bezel, the operative parts being in full lines and the supporting bracket broken away;

Fig. 2, a view looking toward the electromagnet, the parts being removed from the 40 case, dotted lines representing the power wheel;

Fig. 3, a detail section showing one set of fastening screws, one cushioning spring, and the end of the armature;

Fig. 4, a detail perspective of the armature and its spring;

Fig. 5, a similar view of the back-stop for the armature;

Fig. 6, a horizontal section through the 50 armature and also showing one of the frame plates and the armature spring;

Fig. 7, a detail looking toward the inner face of the armature and showing the contact;

Fig. 8, a detail perspective of the front frame plate, the watch or clock movement, and the winding means, separated, and in relative position;

Fig. 9, a view looking toward the inner 60 frame plate, dotted lines representing the position of certain parts of the winding means;

Fig. 10, a vertical section through the winding or actuating wheel, the power maintaining means and the compensating arm,

the power spring and power shaft being in full lines;

Fig. 11, a detail view of the parts of the power maintaining device;

Fig. 12, a detail of a shock absorbing 70 spring; and

Fig. 13, a section showing the parts for holding the clock or watch movement in position.

The operative parts are carried by a front 75 plate 1 and back plate 2 which are spaced apart and connected together by pillars 3. Secured to the face of the front plate 1 is a dial 4. The back of the front plate 1 is concaved or recessed at 5, Fig. 13, and against the rear of the front plate 1 is secured, by the shoulders 6 on the spacing screws 3, a ring 7. The screw-threaded ends 8 of the spacing members 3 pass through the ring 7 (Fig. 3) and engage threads in 80 the plate 1. The ring 7 is thus held firmly against the plate 1 without requiring other fastening means. The inner edge 9 of the ring overhangs the concavity 5.

Instead of building in a watch or clock 90 movement between and connected to the plates 1 and 2 as is proposed in my Patent, No. 1024709, I take any suitable self-contained and standard watch or clock movement 10, Fig. 8, and, after removing the 95 main spring and winding barrel therefrom, apply this movement and secure it in the manner shown in Fig. 13, the rabbeted edge 11 of the front or dial plate of the movement 10 being overlapped by the overhanging inner edge 9 of the ring 7, whereby the movement is firmly positioned in concavity 5 and clamped against the inner face of plate 1. This subject-matter is set forth and claimed in a divisional application, 105 Serial No. 14,488, filed March 15, 1915.

By the utilization of a standard watch or clock movement, I am enabled to obtain all of the advantages inhering in any selected standard movement and to utilize my improved electrically operated winding means for imparting the requisite driving power to the movement. Thus, in Fig. 8, I have shown at 12 the power or driving means of the present invention in position to be applied to the movement 10 prior to the application of the back-plate 2. The driving pinion 13 is adapted to be received in the concavity 14 of the watch or clock movement 10 and to directly mesh with the periphery 115 of the center wheel 15 of that movement, whereby the driving power is applied to the center wheel and the power imparted to the train from the same periphery of said wheel. Furthermore, the provision of a self-contained 120 watch or clock movement permits quick and easy detachment of the movement, as an entirety whenever it requires inspection, cleaning, or repairs.

Passing through the back-plate 2 are the 130

screw-threaded ends 16 of the retaining guides 17. The said supports 17 clamp the back-plate 2 to the pillars or spacing members 3 and the plates 1 and 2 are thus held 5 in proper relation to each other.

The shock absorbing coil springs 18 (Figs. 1, 3 and 12) loosely surround the retaining guides 17, but at their inner ends they are constricted as at 19 and enter a reduced 10 annular portion 20 of the spring support, whereby the spring is held against detachment, but the remaining coils are loose and free from the retaining guides and adapted to permit the latter to move longitudinally 15 in relation to them to absorb vibrations. At the same time, the inner ends 19 of the spring bear against the back-plate 2 and form an end-lock, as it were, to prevent unscrewing of the parts 16.

Referring to Fig. 1, the outer ends 21 of the springs bear against the back of the shell or case 22 which houses the clock, and the proportions of the parts and length of the springs is such that the springs are under 25 constant tension and hold the dial 4 against the spacer shell 23 and through said shell, press upon the bezel 24 and lock it against rattling or looseness where it is connected by screw-threads 25 to the shell 22. No fastenings of any kind are employed to secure the entire apparatus, including the movement 10, electro-magnet, armature, and power means in position. The tension of the springs 18 is such that the pressure they 30 exert on the shell and on the back-plate 2 is sufficient to hold the dial 4 firmly against the ring 23 at all times without requiring separate fastenings and to prevent twisting or chattering due to the vibration to 35 which the clock may be subjected, as for instance, when in use on an automobile. At the same time, the retaining guides 17 being shorter than the springs 18, permit a cushioning and shock absorbing relative movement of the parts without separation. Preferably, there will be but three pillars 3 40 placed at equal distances apart as such arrangement provides for all possible movements. I do not limit myself, however, to the use of but three springs and supports. The shock absorbing devices are set forth and claimed in a divisional application, 45 filed March 15, 1915, Serial No. 14,489.

The hands which travel in front of the dial 4 are shown at 26 and the glass face of the clock at 27. The shell or case is preferably provided with a bracket 28 which is partly broken away in Fig. 1, by which the clock may be secured to the dash of the automobile in suitably inclined position for easy observation.

The power shaft 29 carries the pinion 13 at one end and has its tip 30 journaled in a bearing in the front plate of the movement 10, the pinion 13 being received in the con-

cavity 14 and meshing with the periphery of center wheel 15, as previously explained. The other reduced end 31 of the power shaft is journaled in the back-plate 2. The driving or power wheel 32 is provided with a 70 sleeve 33 loosely surrounding and having a bearing on the power shaft 29. Secured to the sleeve 33 in any preferred manner is a compensating arm 34 (Figs. 9 and 10). An actuating or power coil spring 35 which is 75 connected to the arm at one end, is, at its other end, engaged with a stud or pin 36 (Figs. 1 and 8) on the front plate 1 or the ring 7. The spring 35 and arm 34, through the power wheel and maintaining device 80 hereinafter set forth, drive the power shaft 29 and pinion 13 and thus drive the train.

In my Patent No. 1024709, the driving spring is coiled around the sleeve of the power wheel. I have previously pointed out 85 the operation of a spring of that character. By using the spring 35 and arm 34 or any equivalent of the latter such as a cam or fusee, I obviate the possibility of a slower movement of the train at one time than another.

Reference being had to Fig. 9, when the power wheel 32 is kicked back by the action of the electro-magnet and armature, the spring 35 is placed under tension. Obviously, the farther the power wheel is moved by the electro-magnetic action, the greater will be the tension on the spring 35, within certain limits. Were it not for the employment of the arm 34, disadvantages of 90 difference of operation of the clock or watch train would result, as with the power spring of my Patent, No. 1024709, but the employment of the arm 34, or its equivalent, affords an automatic compensating means. 95 When the arm passes beyond the point where the leverage exerted by the spring through said arm is greatest, while the tension of the spring is increased on such further movement, the travel of the arm correspondingly decreases the leverage and compensates for the increasing tension of the spring. Consequently, the torque exerted on the power shaft 29 is substantially constant. 100 105

Preferably, the travel of the arm is 110 through less than 90°. I provide a stop 37 on the plate 2 which is adapted to engage a stop 38 carried by the power wheel 32. The inner end of the stop 38 extends into a concavity 39 which is provided in the face of 115 the power wheel for the accommodation of the power maintaining device shown in Figs. 8, 10 and 11 and in dotted lines in Fig. 9.

The power maintainer has a driving disk 120 40 which is pinned or screwed onto the end 31 of the power shaft 29 and interposed between this disk and the shoulder of the shaft 29 is a washer 41. Loosely mounted on the hub of the disk 40 is a ratchet wheel 42 125 130

which rests upon the washer 41. Contained within the ratchet wheel 42 is a circular power maintaining spring 43, one of whose ends is engaged with a pin 44 on the driving disk 40, and the other end is engaged with a pin 45 on the ratchet wheel 42. Pivoted to the power wheel 32 is a power transmitting pawl 46 which is held in engagement with the ratchet wheel 42 by a spring 47 carried by the wheel 32 and located in the concavity thereof. The inner end of the pin 38 overlies this spring and prevents it from becoming displaced. To prevent back movement of the ratchet wheel 42, I provide on the plate 2, a retaining pawl 48 pressed by a spring 49.

The tension of spring 35 is transmitted through arm 34 to sleeve 33 and power wheel 32, thence through pawl 46 to ratchet wheel 42 and through maintaining spring 43 to driving disk 40 which turns the power shaft 39, the pinion 13 transmitting the power to the center wheel 15.

As with the power maintainer of my Patent No. 1024709, the spring 43 compensates for the momentary loss of driving power when the electro-magnet and armature are kicking back the wheel 32 to tension the spring 35.

30 The power wheel 32 is provided with a contact pin 50 which is adapted, when the wheel 32 unwinds to a certain point, to engage a contact block 51 (Figs. 4 and 7) on the armature 52.

35 The armature 52 is made in one piece, which permits it to be manufactured as a single stamping at greatly less expense than the armature, and armature lever of my Patent No. 1024708 and it has pivots or 40 trunnions 53 at one end thereof, these being journaled in suitable bearings in the plates 1 and 2 as at 54 (Fig. 3). To the face of the armature is secured a leaf spring 55, one of whose ends—that nearest the pivots 53—bears against a pole of the electro-magnet 56 (Fig. 2) when the armature is in normal position. The leaf spring 55 serves the double purpose of preventing the armature from sticking to the poles of the electro-magnet by the residual magnetism thereof 45 and it also assists slightly in holding the armature away from said poles.

Referring to Figs. 2 and 6, it will be seen that the armature lies in substantially 50 a single plane and that in consequence of its being pivoted at one end only, instead of being carried by a lever which is pivoted intermediate its ends, as is proposed in my Patent No. 1024709, the present armature 52 is adapted to move bodily or as an entirety. Consequently, as previously explained, the relationship of the armature to the poles of the electro-magnet is such that the part of the armature nearest its pivots 53 is always

within the magnetic field of the left-hand pole (Fig. 2) and consequently, on the slightest magnetization of the electro-magnet by even a very weak current, the armature is actuated and thereupon, by a bodily movement, comes within the magnetic field of the other pole of the magnet and an instantaneous or hammer-like kick or snap occurs and a corresponding hammer-like action is exerted on the contact pin 50 of the power wheel 32. As a result of this construction and arrangement, the power wheel is turned back to re-wind the spring 35 to an adequate degree even though the battery current be very weak. As previously explained, whether the battery current be weak or strong, substantially the same driving torque is exerted on the power wheel 32. A spring 57 which is loosely coiled around one of the pivots 53 and is engaged at 58 (Fig. 6) with the armature and at 59 with one of the pillars 3, affords the necessary tension to retract the armature, but without offering much resistance to its attraction by the electro-magnet. A back stop 60 (Figs. 2, 5 and 9) is secured to plate 2 and has a spring finger 61 which yieldingly engages the armature. This stop and finger, by their relationship to the armature (Fig. 2) cause an edge of the stop to engage with most of the effective length of the armature and afford an effective cushioned arrester for the armature on deenergization of the electro-magnet, but as the spring finger has only a limited travel before it strikes the stop body, there is substantially no rebound of the armature when it is retracted. The contact block 51 is suitably insulated from the armature to which it is fastened by screws 62 which also are insulated from the armature and serve to secure the metallic conductor end 63 of the conductor 64 which passes through an opening 65, preferably in line with the pivots 63 and thence to the insulated binding post 66 (Fig. 2) whence the conductor 67 extends to the electro-magnet. The other terminal 68 of the electro-magnet (Fig. 9) is connected to an insulated binding post 69 from which leads a battery wire 70 (Fig. 2). The other battery wire may be connected to any part of the shell or case, as for instance, to one of the screws 71 (Fig. 1) which secures the bracket 28. The current has access through the shell or case to the different metallic parts to the power wheel 32 and thence to the contact pin 50 so that when the latter touches the contact block 51, the circuit is completed and the electro-magnet energized, thereupon attracting the armature and, through the contact pin 50, kicking the power wheel 32 backward to wind up the spring. The direction in which the power wheel 32 is kicked to wind the spring is indicated by the arrow on

said power wheel, as shown in Fig. 8. The direction of movement of the ratchet wheel 42 is shown by the other arrow in Fig. 8.

By running the conductor 64 through the hole 65, no resistance is offered by the tension of the conductor to the free movement of the armature.

If it be assumed that the power spring 35 has been wound, the contact pin 50 will then 10 be out of engagement with the contact block 51. When the spring 35 contracts, due to imparting its power to the train, sufficient 15 to bring said pin 50 into engagement with the contact block 51, the circuit is immediately completed and the electro-magnet 56 energized, whereupon it attracts the armature as before explained and in doing so, kicks the power wheel 32 backward in opposition to the position of the spring 35, 20 thus re-tensioning said spring. During this re-tensioning of the spring there would be a tendency toward cessation of the turning of the train of wheels. To compensate for this and to enable the train to continuously operate, even during the almost instantaneous kicking back of the power wheel 32; the 25 spring 43 having been placed under tension, tends to uncoil and therefore, continues the application of the spring power to the shaft 29, resulting in continuity of driving of the clock train and the keeping of the correct time.

The engagement of the pin 50 and the block 51 is a rolling one which insures a

good electrical contact at all times and the 35 keeping of the contacting surfaces bright.

Having thus described my invention, what I claim as new and desire to secure by Letters Patent, is:

In a clock, the combination with a frame, 40 of a power shaft journaled therein and in metallic contact therewith adapted for driving the train, a power wheel loosely mounted on, and in metallic contact with, the said shaft and adapted for driving it, a ratchet 45 wheel loosely mounted on said power shaft, a driving disk loosely related to the ratchet wheel and secured on the power shaft, a compensating spring connecting the driving disk and the ratchet wheel, a pawl carried 50 by the power wheel and engaging the ratchet wheel, an electric contact on the power wheel, an armature having a contact adapted to be engaged by the contact aforesaid, an electro-magnet in circuit with said contact and said frame, an arm connected to the power wheel, and a contractile coil spring having one end anchored and its other end connected to said arm, said armature being adapted to kick the power wheel 55 to tension said contractile coil spring when the contacts engage.

In testimony whereof, I hereunto affix my signature in presence of two witnesses.

WILLIAM H. THOMPSON.
